SPRAYING APPARATUS FOR ATOMIZING
PAINT AND OTHER LIQUIDSHenri Guido Lemoine, Par Perriers-sur-Andelle
(Eure), FranceApplication July 11, 1933, Serial No. 679,838
In France July 12, 1932

1 Claim. (Cl. 299—140)

This invention relates to a spraying apparatus for atomizing paint and other liquids, which is simple in construction and inexpensive to manufacture although ensuring efficient operation. 5 The principal part of said apparatus occupies so small a space that when taken apart from the liquid container and the source of pressure it may be held in the hollow of the hand.

The apparatus constructed in accordance with 10 the present invention operates much better than guns of more complicated make, but it does not require a very powerful source of pressure, it may for example work perfectly well with the garage apparatus known as "inflator".

15 The invention is substantially characterized in that the atomizer comprises a flat liquid aperture, on either side of which are placed two air ejectors limited by two flat walls in parallel with the axis, the air inlet channel to said ejectors opening upon one of said walls in the direction of the other wall and of the liquid aperture in such a manner that the liquid is drawn in and atomized by two air sheets which cut one another in front of said aperture and that the liquid sheet is limited along two flat surfaces in parallel with the portions of both air jets that are deflected by the second wall of each ejector.

30 The appended drawing shows by way of example a mode of execution of a spraying apparatus constructed according to the present invention.

Fig. 1 is a longitudinal section illustrating the whole apparatus.

35 Fig. 2 is a view drawn in the direction of the arrows 2—2 in Fig. 1.

Fig. 3 is an end view.

Referring more particularly to the drawing, the apparatus as therein shown comprises a body 1 provided with a nozzle 2 for the admission of air pressure in chamber 3 and from which extend horizontal passages 4 opening in front in a second chamber 5 formed in an end piece 6, fixed upon the body 1 by means of a nut 7.

40 Two horizontal channels 8 extending from the chamber 5 through the end piece 6 communicate with oblique channels 9 opening in an orifice 9^a under the lower flat sides 10 of a boss 10^a formed at the outer end of the part 6.

45 Between the two flat sides 10 is provided a middle hollow atomizing valve or a liquid suction nozzle 11 having two sides 11^a in parallel with the axis and with the aforesaid sides 10. The nozzle 11 which is screwed in the end piece 6 is 50 provided with an outlet orifice 12 having prefer-

ably the same shape as the outer profile of the nozzle that is to say flat.

In the most favourable position, the orifice of the atomizing nozzle is so situated that the air jets coming out of the orifices 9^a are divided into 5 two equal portions one of which strikes the side 11^a and the other which is not deflected comes to join in front of said orifice, in the axis, the similar portion of the other air jet.

The passage 13 in the atomizing nozzle is ex- 10 tended inside the end piece 6 by a passage 14 which by the intermediary of a packing inserted between said end piece and the body 1, connects with another passage 16 opening in a vertical channel 17. Said channel reaches down to the 15 liquid inlet nozzle 18 which may be connected to a paint pot or other container by means of a suitable piping or in any other way.

The channel 17 may communicate at its upper 20 end with the atmosphere either directly at 19 as shown in the drawing or by the intermediary of a valve which is normally open.

In the case illustrated in the drawing, when the connections between the air pressure source and the liquid source are made, it will be necessary 25 only to close the aperture 19 with one finger of the hand that holds the apparatus in order to cause the liquid or the paint to be projected in the shape of a flat sheet having parallel edges.

In fact the air jet coming out of both orifices 9^a 30 is divided into two portions. One of them is not deflected and meets the similar portion of the other air jet along the axis in front of the liquid aperture drawing in and atomizing said liquid. The other portion of both air jets is deflected by 35 the side 11^a and limits the liquid sheet along a plane surface in parallel with the axis. The elementary effects thus obtained are really more complicated but the result is that which has just been stated, that is to say the projection of a 40 strictly flat liquid sheet.

The discharge and the flattening may be regulated by screwing and unscrewing the atomizing valve 11, when in its most favourable position. 45 When it is desired to stop the projection it is only necessary to raise the finger so as to uncover the aperture 19. This resulting in a short circuiting of the suction along 12—13—14—17—19 so that the atomizing valve now discharges air 50 only.

It will be evident that the atomizing end piece which is a distinctive feature of the present invention could also be used with apparatus in which air pressure is caused to act upon the liquid. 55

What I claim and desire to secure by Letters Patent of the United States is:—

5 A spraying apparatus for atomizing paint and other liquids, comprising a frame having an air inlet formed therein, a liquid suction nozzle connected with said frame, a tubular middle spout integral with said nozzle and having a liquid discharge aperture formed therein, said spout being flat and having two outer parallel plane surfaces, 10 two plane parallel walls on both sides of said aperture, said walls being parallel with the plane surfaces of said spout, and means forming two oblique converging passages connected with said

air inlet, each of said passages opening through an orifice upon said plane walls at a distance from said liquid discharge aperture, the obliquity of said passages and the position of their orifices being such that a portion of the air jet issuing from one of them meets the corresponding portion of the air jet coming out of the other orifice in front of the liquid discharge aperture, whereby the other portion of the air jet from both orifices strikes the corresponding outer plane surface of 10 the tubular spout. 5
